ATTORNEY,

UNITED STATES PATENT OFFICE.

ARTHUR RODMAN, OF HOLDER, ILLINOIS.

BAND-CUTTING FORK.

SPECIFICATION forming part of Letters Patent No. 396,431, dated January 22, 1889.

Application filed April 23, 1888. Serial No. 271,548. (No model.)

To all whom it may concern:

Be it known that I, ARTHUR RODMAN, of Holder, in the county of McLean and State of Illinois, have invented a new and Improved 5 Band-Cutting Fork, of which the following is a full, clear, and exact description.

This invention relates to forks for handling grain, and has for its object to provide a grain-fork so constructed that the grain may be 10 handled and the fastening cord or band severed simultaneously by means of the fork.

The invention will be set forth in the following description, and pointed out in the claims.

15 Reference is to be had to the accompanying drawings, forming a part of this specification, in which similar figures of reference indicate corresponding parts in both the views.

Figure 1 is a perspective view, with handle 20 broken away, of a grain-fork constructed in accordance with this invention. Fig. 2 is a detail showing a modification in the cutter.

In unfastening sheaves of grain preparatory to shaking before the straw is passed through 25 the thrashing-machine the services of two men are required to cut the bands or cords holding the sheaf. By means of this invention these men may be dispensed with and a man using the fork can cut the bands and 30 handle the straw simultaneously.

The fork is constructed as follows: The head 1 of a grain-fork, 2, is provided with a post, 3, shown as screwing into the same, and formed with an enlarged part, 4, in which is 35 supported a bar, 5, having one end fastened by a screw, 6, in a socket-piece, 7, secured by screws 8 to the handle 9 of the fork. The other end of bar 5 is forked, as shown tapering in form at 10, and is riveted to a cutting-blade, 11, projecting over the hollow portion of the fork 2, with its flat side at right

angles thereto. The cutter 11 is formed preferably, as shown, with shoulders 12, having bearded cutting-edges 13, which cut the band of the sheaf as the fork is thrust into the straw. The blade or cutter 11, which is preferably of steel, is formed thicker at the center along the rib 14 to render the cutter strong. In lieu of the bearded cutting-edges 13 the shoulders 12 of the cutting-blade 11 may be 45 formed with plain cutting-edges 15, as shown in Fig. 2. If desired, the cutter and its attaching portions may be removed from the fork.

By means of this invention a grain-fork is 55 provided by means of which the handling of straw-sheaves is greatly expedited and the expense thereof reduced.

Having thus described my invention, what I claim as new, and desire to secure by Letters Patent, is—

1. An attachment for grain-forks, consisting of the tapering blade 11, having shoudered cutting-edges 12 on opposite sides, and provided with the bar 5, the screw-threaded 65 post 3, having the enlarged and apertured part 4, and the socket-piece 7, substantially as described.

2. The combination, with the fork 2, the handle 9, provided with the socket-piece 7, 70 and the post 3, secured to the head of the fork and having apertured enlargement 4, of the bar 5, secured in the socket-piece and enlargement of the post, and the cutting-blade 11, provided with the shoulders 12, having 75 bearded cutting-edges 13, substantially as herein shown and described.

ARTHUR RODMAN.
